ENGINE STARTING MECHANISM

Raymond P. Lansing, Montclair, N. J., assignor to
 Eclipse Aviation Corporation, East Orange,
 N. J., a corporation of New Jersey

Application May 27, 1930, Serial No. 456,273
 Renewed March 9, 1937

11 Claims. (Cl. 123—179)

This invention relates to mechanism for use in starting internal combustion engines.

One of the objects of the invention is to provide novel engine starting mechanism including 5 ignition current supply means, the latter being operable with said mechanism or independent thereof.

Another object of the invention is to provide 10 novel engine starting apparatus of the inertia type in combination with a current supply means adapted to be operated first by the starter and thereafter by an auxiliary means.

Another object of the invention is to provide, 15 in combination with a booster magneto for airplanes, an engine starter adapted to simultaneously drive the engine and booster magneto, and an auxiliary means for continuing the operation of the magneto during the last stage of the engine cranking action, or even after discontinuance of the cranking action, thus supplementing 20 the drive from the starter and producing a more intense spark in the engine cylinders than would otherwise be produced. A further function of the last-named means is to supplement the cranking action by imparting a further degree of acceleration 25 to the engine engaging member.

A further object is to provide novel manual means for operating a booster magneto.

Two embodiments of the invention are illustrated in the accompanying drawings, wherein 30 like reference characters refer to like parts throughout the several views. It is to be expressly understood that the drawings are for the purpose of illustration only, and are not designed 35 as a definition of the limits of the invention. In the drawings,

Fig. 1 is a longitudinal section of one embodiment of the invention;

Fig. 1a is a view in perspective of a portion of 40 the meshing mechanism;

Fig. 2 is a sectional view taken along the line 2—2 of Fig. 1;

Fig. 3 is a similar view to Fig. 2, showing a 45 portion of a second embodiment of the invention; and

Fig. 4 is a sectional view taken along the line 4—4 of Fig. 3.

Referring to Fig. 1, the engine starter comprises a housing embodying an inner section 6 50 that is preferably formed of aluminum, an intermediate section 7 that is removably secured to section 6 as by means of bolts 8, and an outer section 9 that is secured to section 7 in any suitable manner as by means of screws (not shown). The inner section is provided with a flange 10

that is adapted to be bolted or otherwise removably connected to the engine crank case, a portion of the latter being diagrammatically illustrated at 11. The intermediate housing section 7 is provided with an end wall or diaphragm 12 having a lateral projection boss 13 in which are positioned a pair of ball bearings 14 for rotatably supporting a flywheel 15, which is of small size and weight and which is adapted to be rotated at very high speeds, whereby energy may be 10 stored therein for starting the engine.

Means are provided for manually rotating the flywheel 15. In the form shown, said means includes a cranking shaft 16 which is disposed substantially at right angles to the axis of rotation 15 of the flywheel 15 and is rotatably mounted in the intermediate housing section 7. The diaphragm 12 is provided with a lug 17 carrying a ball bearing 18 for rotatably supporting the inner end of shaft 16, and the side wall of section 7 carries a ball bearing 19 for rotatably supporting the outer end of the cranking shaft. A spacing sleeve 20 surrounds the intermediate portion of the cranking shaft and bears at its opposite ends against the inner faces of the bearings 18 and 19, whereby the latter are maintained at proper spaced relation.

The cranking shaft 16 is provided with an enlarged portion 21 which extends laterally from the outer walls of section 7 and carries closely adjacent the end thereof, a transverse pin 22 adapted to be engaged by a hand crank (not shown), whereby said shaft 16 may be manually rotated. The inner end of shaft 16 has drivably connected thereto in any suitable manner, a bevel gear 23 that meshes with a bevel gear 24 which is drivably connected to a stub shaft 25 which is preferably formed integral and concentrically with the closed end 26 of the barrel 27 that is rotatably mounted as by means of ball bearings 28 in the inner housing section 6.

Three planetary gears, one of which is shown in section at 29 while the others are omitted for clarity of illustration, are rotatably mounted on the outer faces of the barrel end 26. As shown, the mounting of each planetary gear is constituted by a screw 30 that is disposed parallel to stub shaft 25 and is threaded at its inner end into barrel end 26. Surrounding the shank of each of the screws is a sleeve 31 having its inner end countersunk in barrel end 26 and interposed between the sleeve and the planetary gears in a ball bearing 32. The planetary gears are spaced at angular intervals of 120 degrees around the end of the barrel, and screws 30 carry on their 45 50 55 60 65 70 75 80 85 90 95 100 105 110 115 120 125 130 135 140 145 outer ends a ring 33 which constitutes a retainer for each of the sleeves 31 and ball bearings 32.

An internal spur gear 34, which is rigidly attached to the inner surface of housing section 6 5 as by means of screws or studs 35, surrounds and has meshing engagement with each of the planetary gears 29. The latter also mesh with a sun gear 36 which is rotatably mounted by means of a bushing 37 on the stub shaft 25. The sun gear is preferably formed integrally with an internal spur gear 38, which is likewise rotatably mounted on the stub shaft 25, and said internal gear meshes with a pinion 39 formed on one end of a bell-shaped member 40, the large end of 10 said bell-shaped member being cut to form a spur gear 41. A pinion 42 which is formed integral with the inner end of a stub shaft 43 meshes with the spur gear 41. The stub shaft 43 extends through and is drivably connected to 15 the hub 15^a of the flywheel, and longitudinal movement of said shaft relative to the flywheel is prevented by means of a flange 43^a provided on the shaft adjacent pinion 42 and a nut 44 that is threaded onto the outer end of said shaft 20 and is held in position by means of a lock washer 45 that has abutting engagement with the outer face of flywheel 15.

The energy stored in the flywheel is adapted to be imparted to a clutch or jaw member 46 30 carried by the crank shaft 47, or an extension thereof, of the engine to be started and for this purpose the flywheel is drivably connected through the train of gears described above with a clutch or jaw member 48 that is adapted for movement into, but is normally out of, engagement with jaw member 46.

The energy stored in the flywheel 15 is so great that damage would result to the starter parts at the time the starter is connected to the engine if said flywheel were rigidly connected to the 40 clutch member 48. Accordingly, a yielding driving connection is provided between the flywheel and the clutch member 48. In the form shown, the yielding driving connection is constituted by a clutch of multiple disc type, said clutch being positioned within the rotatable barrel 27. A number of the clutch discs 49, which are annular in form, are splined at their outer peripheries to the inner surface of the barrel 27. The remaining discs of the clutch are splined at their inner peripheries to the outer surface of an internally threaded nut 50 which is provided intermediate its ends with a flange 51. The clutch discs 49 are held between flange 51 and the inner face of the 45 end walls 26.

Yielding means are provided for varying the frictional engagement of the discs whereby the amount of torque transmitted by said discs may be varied. For this purpose the inner surface of the inner end of barrel 27 is threaded to receive 50 an adjustable nut 52 which has engagement with a spacer ring 53 provided with a plurality of equi-spaced pins 54, each of which extends into a coil spring 55. These springs bear at one end 55 against flange 51 and serve to hold the clutch discs 49 in frictional engagement. By adjusting the position of nut 52 relative to barrel 27 the compression of the springs may be varied, thereby varying the pressure exerted by said springs 60 through flange 51 on the clutch discs. Any suitable locking means, such as is shown at 56, may be employed for locking the nut 52 in adjusted 65 position.

A threaded shaft 57 is positioned within the 70 internally threaded nut 50, the shaft being adapt-

ed for rotary and longitudinal movement relative to said nut. The outer end of shaft 57 carries a stop nut 58 adapted to engage a suitable shoulder formed interiorly of nut 50 whereby longitudinal movement of the shaft is positively limited. The inner end of shaft 57 is provided exteriorly with longitudinal splines which coact with the interiorly splined hub portion 48^a of the jaw 48. A coil spring 59 is interposed between jaw member 48 and the adjacent end of shaft 57 to resist movement of said jaw towards the shaft and, if desired, the shaft may be provided with a recess to receive the adjacent end of spring 59. Oil-sealing means 60 are preferably provided for the engine end of the starter to prevent seepage of oil 10 from the engine crank case into the starter housing.

Means are provided for moving shaft 57 and jaw 48 toward the jaw member 46 whereby said jaws may be moved into driving engagement and the energy stored in flywheel 15 may be rendered available for rotating crank shaft 47. As will be pointed out more fully hereafter, said means also serve to establish the driving connection between the magneto and flywheel. In the form shown, the starter is provided with a longitudinally and concentrically disposed rod 61 which slidably extends through jaw member 48, threaded shaft 57, the closed end 26 of the barrel, and stub shaft 25, the outer end of said rod terminating closely adjacent the inner face of pinion 42. The inner end of rod 61 is of reduced diameter to provide a shoulder 62 which normally is in abutting engagement with the outer end of threaded shaft 57. The inner extremity of rod 61 is threaded to receive a nut 63 which bears against the inner face of jaw member 48.

The outer end of rod 61 is provided with a transversely extending pin 64 which passes through a slot 65 provided in one end of a lever arm 66, the opposite end of said arm being rigidly connected to a rockshaft 67 journaled in the starter housing. One end of the rockshaft 67 projects through the starter housing and has fixedly attached thereto a bell crank lever adapted to receive a rod or cable (not shown) whereby said rockshaft may be manually rotated. A coil spring 69 surrounds rockshaft 67 and has one end thereof in engagement with lever arm 66, the other end of said spring being anchored in any suitable manner whereby the same normally maintains rod 61 in the position shown in Fig. 1 with jaw 48 in retracted or non-driving position.

Ignition current supply means such as a small, light booster magneto 70 is conveniently mounted 55 on the starter housing and means are provided for drivably connecting said magneto and flywheel whereby the latter may drive the magneto at high speed. In the form illustrated, magneto 70 is mounted on the end of housing section 9 60 in such a position that the magneto armature shaft 71 extends substantially at right angles to the axis of flywheel 15. A pinion 72, which is carried on the outer end of shaft 71 meshes with a bevel gear 73 fixedly secured to one end of a 65 shaft 74 which is rotatably mounted in a housing 75 provided on the side of the starter housing. The inner end of shaft 74 carries a pinion 76 adapted to be drivably engaged but normally out of engagement with a bevel gear 78 which is 70 slidably mounted on the enlarged end of crank shaft 16.

A slot 79 is provided in shaft 16 and slidably extending therethrough, at substantially right angles to the longitudinal axis of the shaft, is a 75

pin 80 which engages at its opposite ends the hub portion of bevel gear 78, the pin thus constituting a driving connection between shaft 16 and said bevel gear. The bevel gear 78 is normally maintained out of driving engagement with pinion 76 by means of a spring 81 which is preferably of the single helico-volute type and which surrounds the enlarged portion 21 of shaft 16, the outer end of said spring bearing against a collar 82 which surrounds portion 21 and is held in place thereon by pin 22. The inner end of spring 81 bears against a suitable portion of the gear 78. Means are provided for moving gear 78 upwardly into driving engagement with pinion 76 against the tension of spring 81 and said means are preferably so constituted as to be actuated by lever 68, rockshaft 67 and arm 66. As shown, a rod 83, which may be formed in sections if desired, slidably extends through the hollow cranking shaft 16, the outer end of said rod having abutting engagement with pin 80 and the inner end of the rod being provided with a U-shaped head 84. Diagonally disposed slots 85 are provided in the opposite sides of head 84 and through said slots project the opposite ends of the pin 64 carried by rod 61. One end of each slot 85 is preferably enlarged, and normally pin 64 extends through said enlarged portions.

The operation of the apparatus is as follows: The operator engages the hand crank (not shown) with pin 22 and rotates cranking shaft 16. This movement is transmitted, through the train of gearing described, to flywheel 15 whereby the latter may be rotated at high speed and energy stored therein for starting the engine. As soon as the flywheel is brought to the desired speed of rotation the operator actuates lever 68 to rotate rockshaft 67 which motion is transmitted to the arm 66 whereby the latter is moved in a clockwise direction as viewed in Fig. 1. The movement of arm 66 is transmitted through pin 64 to rod 61 forcing the latter to the right as viewed in Fig. 1. Threaded shaft 57, which is also rotated by the flywheel through the train of gearing, the multiple disc clutch and the nut 50, and which also rotated during the manual cranking operation, is forced to the right by shoulder 62 whereupon spring 59 is effective to move jaw 48 into driving engagement with jaw 46 and the energy of the flywheel is imparted to crank shaft 47 to rotate the same.

Simultaneously with the movement of rod 61, pin 64 is effective through the slotted head 84 to move rod 83 upwardly. Pin 80, which has abutting engagement with the rod 83, is also forced upwardly, against the tension of spring 81 and bevel gear 78 is thus moved into meshing engagement with pinion 76, whereupon the flywheel is effective to rotate the magneto armature shaft 11. The magneto now supplies starting current to the engine and when the latter starts under its own power the speed of the crank shaft 47 is such as to cause jaw 46 to overrun jaw 48, whereupon the inclination of the teeth of said jaws forces jaw 48 out of driving position. When the operator releases lever 68 spring 69 returns the rods 61 and 83 to normal position and spring 81 is now effective to demesh gear 78 by moving the latter downwardly. It will be noted that gear 78 rotates in unison with shaft 16, which is a low speed shaft and hence the meshing of said gear 78 with pinion 76 is readily effected.

In Fig. 2 there is illustrated one embodiment of the auxiliary magneto drive. The casing 75 is provided with a wall or diaphragm 90 cooperating

with a dependent casing 91 attached to casing 75 by any suitable means for supporting a reduction gear train. An operating shaft 92 is supported in a bearing 93 in the wall 90 and a bearing 94 in the casing 91. The shaft 92 extends beyond the exterior of the casing 91 and has attached thereto a crank arm 95 by means of a set-screw 96.

An aperture 97 is shown at the end of the crank arm for receiving a handle (not shown). The crank arm 95 abuts against the casing 91 and is adapted to cooperate with a collar 98 attached to the other end and abutting the wall 90 for maintaining the shaft 92 in proper position and preventing longitudinal movement. Within the casing the shaft 92 has splines upon which is mounted a driving member 100 spring pressed into cooperative relation with a member 101 by means of a spring 102 supported between member 100 and a collar on the shaft 92.

The engagement between members 100 and 101 is by means of ratchet teeth 103 and 104 which will permit relative rotation in one direction only. The ratchet teeth will slip by each other in one direction during relative rotation but will positively engage when rotated in the opposite direction. The member 101 is slidably mounted on the shaft 92 and comprises a combined clutch and gear, the latter being designated 105. The gear member 105 is constantly in mesh with a gear 106 preferably formed integral with a gear 107. Gear 107 is mounted on a shaft 108 supported between the wall 90 and casing 91, and is constantly in mesh with a gear 109 which is preferably made integral with a gear 110. Gears 109 and 110 are mounted on a shaft 111 supported by wall 90 and casing 91. Gear 110 drives a gear 112 mounted rigidly on a shaft 113, which is provided at its opposite end with a bevel gear 114 constantly in mesh with gear 73, the gear 73 also being in mesh with the driving gear 72 of the booster magneto.

In the embodiment shown in Fig. 3 shaft 92 is mounted in the bearing 93 in wall 90 and bearing 94 in casing 91. The shaft is splined as at 99 and the ratchet clutch member 103 is mounted on the shaft the same as in Fig. 2. Also on the spline shaft 92 is mounted a drum 115 having a narrow circular recess 116 in its periphery and a wide circular recess 117 in its outer face. Member 115 is held on shaft 92 by means of a cap nut 118 screw threaded on a reduced portion of the outer end of the shaft 92. The end of the casing 91 is closed by means of a cover plate 119 secured in any suitable manner such as screws (not shown). Coiled within the narrow circular recess 116 is a cord or flexible cable 120, the convolutions of which are around each other and held in place by the side walls of the recess 116. The inner end of cord 120 is attached to member 115 while the outside end extends through an aperture 94a (Fig. 4) to the outside of the case. Within recess 117 is mounted a clock spring 124 having its inside end fixed to member 115 and its outside end attached to a terminal member 122 which extends outwardly and is attached to the cover plate 119. The convolutions of the spring 124 are wound in the opposite direction from the convolutions of the cord 120 and, therefore, the spring tends to keep the cord wound in its proper position. The initial tension of the clock spring 124 may be adjusted by rotating cover plate 119 and member 122 until such tension is obtained and then securing the cover in place.

When it is desired to start the engine by the inertia starter the device will operate in the man-

ner above described, but when it is desired to increase the intensity of the spark derived from the operation of the booster magneto, the latter may be driven from the auxiliary driving means.

5 The driving shaft 92 of the auxiliary driving means may be rotated either by the hand crank of Fig. 2 or the cord 120 of Fig. 3. In using the cord 120 the operator causes the spring to be wound tightly within the drum 115, so that upon 10 release of the cord the spring acts not only to rewind the cord in the groove 116 but also to drive the booster magneto armature shaft through the ratchet clutch members 103 and 104 and the train of gears described.

15 When the auxiliary driving means is used the engine starter may or may not rotate with the booster magneto depending upon whether the gears 76 and 78 are in mesh. When the starter is independently energized, and gears 76 and 78 20 are brought into mesh, the gear train of the auxiliary drive is actuated. However, because of the ratchet clutch members 103 and 104 attached to the operating means and gear train, respectively, of the auxiliary driving means, a relative 25 rotation therebetween is permitted in one direction. Under these conditions the ratchet jaws will slip by each other forcing member 100 out of contact with member 101 against the spring 102, so that the manual actuating means will not 30 be affected.

There is thus provided novel engine starting mechanism so constituted that the engine on which said mechanism is mounted may be started positively with the aid of a booster magneto 35 adapted to be driven either from the starter or by supplemental means without the necessity of disconnecting or adjusting any of the parts of the mechanism. It will be understood that current supply means other than a booster magneto 40 may be employed.

While only two embodiments of the invention have been illustrated and described in detail it will be obvious to those skilled in the art that certain changes, modifications, additions and 45 omissions may be made in the details of construction and arrangement of the parts without departing from the spirit and scope of the invention defined in the appended claims.

What is claimed is:

50 1. In combination with engine starting apparatus, current supply means, a gear train between the starting apparatus and the supply means, said gear train being operable to transmit driving effort either to or from said starting apparatus, and auxiliary spring driving means operable through said gear train for simultaneously actuating said supply means and starting apparatus.

55 2. In combination with an inertia starter of the type having an inertia member in which energy is stored prior to establishment of driving connection with the engine to be started, a booster magneto, a gear train connectable with the starter for driving the magneto, and a manual means for driving the magneto and starter simultaneously, the drive to the latter being by way of said gear train.

60 3. In an engine starting mechanism, in combination, a flywheel, a magneto, a gear train interposed between said flywheel and magneto, driving means for both said flywheel and gear train, said gear train having a portion drivably connecting the flywheel and engine and a second portion drivably connecting the flywheel and 65 magneto, said second portion being operable to

transmit driving effort from said flywheel to said magneto when said first-named driving means is not in use, and means for automatically disconnecting said first-named driving means from the magneto when the latter is being driven by the flywheel, acting through said second portion of the gear train. 5

4. In an engine starting mechanism, in combination, a booster magneto, driving means therefor comprising an inertia starter normally disconnected therefrom and means for connecting the inertia starter with the booster magneto, an auxiliary driving means normally connected therewith including a gear train and a manually rotatable element connected together by a spring 10 pressed one-way ratchet but adapted to separate against the spring pressure when the inertia starter drives. 15

5. In a starting mechanism for internal combustion engines, in combination, a current generator operable to produce igniting sparks in the engine cylinders, means for turning over the engine crankshaft during the operation of said current generator, said turning means comprising a gear train for actuating said crankshaft, means 20 for simultaneously connecting said gear train with the engine crankshaft and current generator, and auxiliary driving means for said current generator, said auxiliary driving means being also operable through said gear train to continue 25 the cranking operation as long as said gear train remains connected with said crankshaft, said last-named operation being made possible by virtue of the connection theretofore established 30 between said gear train and current generator. 35

6. In a starting mechanism for internal combustion engines, in combination, a current generator operable to produce igniting sparks in the engine cylinders, means for turning over the engine crankshaft during the operation of said current generator, said turning means comprising an inertia member and a gear train for actuating said crankshaft, means for simultaneously connecting said gear train with the engine crankshaft, and with the current generator, and auxiliary driving means for said current generator, said auxiliary driving means being also operable through the connection theretofore established between said current generator and gear train to continue the cranking action after the 40 energy stored in said inertia member has been 45 partially expended.

7. In combination with an engine starter and a booster magneto, a gear train in a plurality of sections, one section of which drivably connects the magneto and starter and another of which includes a member movable to engage a member of the engine to be started, means including a third section of said gear train for actuating both said magneto and engine member concurrently, and additional means for actuating said starter through only the second named section of said gear train. 55

8. In combination with engine starting apparatus, current supply means, a gear train between the starting apparatus and the supply means, said gear train being operable to transmit driving effort either to or from said starting apparatus, and auxiliary driving means operable through said gear train for actuating said supply 60 means and starting apparatus. 65

9. In an engine starting mechanism, in combination, a booster magneto, driving means therefor comprising an inertia starter normally disconnected therefrom, means for connecting the 70 magneto and engine member, and auxiliary driving means operable through a gear train to 75

inertia starter with the booster magneto, and an auxiliary driving means connected therewith including a gear train and a manually rotatable element normally connected together but adapted to separate when the inertia starter drives.

5. 10. In an engine starting mechanism, in combination, a booster magneto, driving means therefor comprising an inertia starter normally disconnected therefrom, means for connecting the inertia starter with the booster magneto, and an auxiliary driving means connected therewith including parts normally connected together but

adapted to separate when the inertia starter drives.

11. In combination with an inertia starter of the type having an inertia member in which energy is stored prior to establishment of driving connection with the engine to be started, a booster magneto, means connectable with the starter for driving the magneto, and a manual means for driving the magneto and starter simultaneously, the drive to the latter being by way of said 10 connectable means.
